UNITED STATES PATENT OFFICE

132,930

DESIGN FOR A HARD-SURFACED COMPOSITION TILE FLOOR COVERING

Bernard J. Walker, Islington, Mass., assignor to
Bird & Son, Inc., East Walpole, Mass., a corporation of Massachusetts

Application December 18, 1940, Serial No. 97,433

Term of patent 14 years

To all whom it may concern:

Be it known that I, Bernard J. Walker, a citizen of the United States, residing at Islington, in the county of Norfolk and State of Massachusetts, have invented a new, original, and ornamental Design for Hard-Surfaced Composition Tile Floor Covering, of which the following is a specification, reference being had to the accompanying drawing, forming a part thereof.

The figure of the drawing is a plan view of hard-surfaced composition tile floor covering embodying my new design, the design being subject to such repetition as may be necessary to cover any given floor or desired portion thereof.

The essential features of the floor covering reside in the individual hollow squares with striations of each running at right angles to adjacent hollow squares and with the center square portion of each having striations at right angles to the striations of its surrounding hollow square.

I claim:

The ornamental design for hard-surfaced composition tile floor covering, as shown and described.

BERNARD J. WALKER.
